2,611,410

BILLFOLD WITH INTERMITTENTLY
REINFORCED EDGE

Samuel J. Smallman, Passaic, N. J., assignor to
I. Smallman and Sons Company, New York,
N. Y., a corporation of New Jersey

Application December 13, 1949, Serial No. 132,646

1 Claim. (Cl. 150—38)

1

This invention relates to billfolds or wallets. More particularly, it is directed to a novel edge reinforcement for a bill-fold.

Billfolds generally comprise a number of leaves or layers of natural or artificial leather, or other suitable fabric arranged to form compartments and/or pockets for bills, papers, cards, stamps, etc. Customarily, the several leaves are united by stitched seams extending around two or more edges of the billfold, and the arrangement is such that the billfold may be folded about a transverse center line.

In normal usage, billfolds are folded and unfolded several times a day, and are frequently inserted in and withdrawn from the wearer's pocket. This causes wear, particularly on the edges of the billfold and strains on the stitched seams. Consequently, the billfold usually wears out at its edges or else the edges may come apart due to loosening or breaking of the seam stitches.

Various means have been proposed to prevent or eliminate this edge wear in billfolds. Generally, however, the edge reinforcements proposed have made the billfolds stiff and rigid. This is highly undesirable, a flexibility of the billfold is an important characteristic, particularly in the hip pocket type.

In some very expensive, custom made billfolds, the edges have been reinforced without detracting from the flexibility of the billfold. This has been effected by individually securing separate metal clips to the corners of the billfold and in spaced relation along the billfold edges. The clips, projecting somewhat beyond the edges of the leather leaves, protect the billfold edges, while the gaps or spacing between the clips provides for flexibility. However, this reinforcing has not been applicable to less expensive billfolds, because of the high labor costs involved in individually securing the separate metal clips to the billfold edges. This additional cost can be justified only in billfolds selling for several times the price of an average billfold.

The present invention is directed to attaining such edge reinforcing in a novel and inexpensive manner such that a low cost billfold, in the folded condition, has the same appearance as one of the mentioned expensive billfolds. To this end, an edge reinforcement is formed from a single strip of metal die cut, or otherwise formed, with the appearance of a comb. Thus, the reinforcement comprises a long, narrow continuous strip of flexible metal having uniform length, substantially rectangular, spaced projections extending from one edge. These projections are of different

lengths, the two longest being located so as to eventually form the corner reinforcements on one section of the billfold.

Either during the formation of the strip, or 5 subsequent thereto, the projections are bent into a U-shape so as to form a series of channels having one flange integral with and connected by a narrow strip. At the same time, the strip as a whole is bent edgewise into a U-shape.

10 The so-formed strip is then slid over two sides and an end of the billfold, with the continuous strip lying against the inner wall of the billfold and the free ends of the projections lying along the outer wall. The assembly is then placed between dies having a U-shape pressure surface conforming to that of the reinforcement. The dies are then closed to simultaneously crimp all of the projections on the billfold edge. The opposite section of the billfold is similarly reinforced.

15 With the foregoing in mind, it is an object of the present invention to provide an improved edge reinforcement for billfolds without detracting from the flexibility of the billfold.

20 Another object is to provide an inexpensive edge reinforcement having the same outward appearance as reinforcements used only on expensive billfolds.

25 These, and other objects, advantages and novel features of the invention will be apparent from the following description and the accompanying drawing. In the drawing:

Fig. 1 is an inside elevation view of an opened billfold embodying the invention.

30 Fig. 2 is an outside elevation view of the folded billfold.

Fig. 3 is a plan view of a typical crimping die used to perform the invention.

35 Figs. 4 and 5 are sectional views of the crimping operation.

40 Referring to the drawings, the invention is illustrated as applied to a billfold 10 having an inner wall 11, an outer wall 12 and a wall 13 co-operable therewith to provide compartments or pockets. Billfold 10 is exemplary of any desired type of billfold, and its constructional details form no part of the present invention.

45 The side and end edges of the billfold are provided with a pair of identical reinforcements 20 formed in accordance with the present invention. Each reinforcement comprises a single strip of thin flexible metal cut and shaped to provide a continuous elongated narrow strip 21 integral with lateral projections 22, 23. These projections

are substantially rectangular in plan and of uniform length.

Reinforcement 20 is bent about its longitudinal center line to form a channel, as shown in Fig. 4, and is bent about two transverse lines to have an overall U-shape. As finished, it comprises a series of individual channels 22, 23 having one flange integral with and united by strip 21.

Each reinforcement 20 is then slipped over an end of billfold 10 so that the end and side edges 10 lie in the channels, the longer channels 22 forming the corner reinforcements. Strip 21 lies against inner wall 11, being spaced inwardly from the edges, and projections 22, 23 lie, in spaced relation along the outer billfold wall 12. Thus, 15 in the folded condition of the billfold, as seen in Fig. 2, the effect is that of a plurality of individually attached clips along the billfold edges.

The reinforcements are crimped to the billfold by suitable dies such as 30, 30', each having a 20 semi-cylindrical U-shape groove 31, 31' corresponding to a reinforcement 20. When the dies close on the reinforcement, a curvature is imparted to reinforcement 20 (Fig. 4) with the corner edges, such as 24, 26 "biting" into the 25 billfold walls.

All of the projections are simultaneously clipped to the billfold, eliminating the costly and laborious individual clipping previously used. This simultaneous securement is due to the use 30 of the integral joining strip 21 between the several clips. This strip is spaced inwardly of the billfold edges, being concealed when the billfold is folded. As it is thin, it does not hinder flexibility of the billfold.

While a specific embodiment of the invention

has been shown and described in detail to illustrate the application of the principles thereof, it should be understood that the invention may be otherwise embodied without departing from such principles.

What is claimed is:

In a billfold of flexible material a U-shaped edge reinforcement overlying an end and two side edges of the billfold and comprising a plurality of U-shape metal clips arranged in longitudinally spaced relation along such edges, each clip having one leg overlying an inner billfold surface and the other overlying an outer billfold surface, and a narrow metal strip integral with such one leg of each clip and extending along such inner wall surface in inwardly spaced relation to such edges whereby, when the wallet is folded, the edges appear to be reinforced by individual spaced clips.
